UNITED STATES PATENT OFFICE.

CARL ERMERT, OF CINCINNATI, OHIO.

DESIGN FOR A TOY COUCH.

Application filed June 12, 1922. Serial No. 2,649. Term of patent 7 years.

To all whom it may concern:

Be it known that I, CARL ERMERT, a citizen of the United States, residing at Cincinnati, in the county of Hamilton and State of Ohio, have invented a new, original, and ornamental Design for Toy Couches, of which the following is a specification, reference being had to the accompanying drawing, forming part hereof.

In the drawings:

Fig. 1 is a side perspective view of a toy couch embodying my invention;

Fig. 2 is an end view thereof; Fig. 3 is a view of the other end; and Fig. 4 is a plan view.

I claim:

The ornamental design for a toy couch, substantially as shown.

CARL ERMERT.
